UNITED STATES PATENT OFFICE.

PAUL PRIEM, OF HEIDENHEIM, GERMANY, ASSIGNOR TO AMERICAN VOITH CONTACT COMPANY, INC., OF NEW YORK, N. Y., A CORPORATION OF NEW YORK.

WOOD GRINDER.

Application filed February 24, 1923. Serial No. 621,117.

To all whom it may concern:

Be it known that I, PAUL PRIEM, a citizen of the Republic of Wurtemberg, Germany, residing at Heidenheim on der Brenz, Germany, have invented certain new and useful Improvements in Wood Grinders, of which the following is a specification.

My invention relates to wood grinders with mechanical feed, and the object of my 10 invention is to provide means for so automatically regulating the pressure against the grind stone that the latter may be driven at a substantially constant load and speed. This regulation is accomplished according 15 to the invention, through means responsive to the varying demand on the driving motor to maintain the stone at constant speed.

The underlying thought is susceptible of embodiment in various forms of equipment, 20 some of which are illustrated in the accompanying drawings, in which—

Fig. 1 is a more or less diagrammatic broken side elevation of a wood grinder installation in which my invention is embodied 25 in one form; and

Figs. 2, 3, 4 and 5 are similar views of different embodiments of the invention.

Referring to Fig. 1, I have indicated at 5 an electric motor of constant speed type, 30 which drives the grind stone 6 through any suitable operating connection, such as a belt or chain 7. Associated with the grind stone is a series of press plungers 8, each working in its independent feed chamber 9 to force a 35 charge of wood blocks 10 against the stone. Each of the plungers is fed forward by a pinion 11 engaging the rack 12 on the stem of the plunger and driven through a chain connection 13, which in turn is driven by a 40 chain 14 running over one of the sprocket wheels 15. The chain 14 is driven from the pinion 16 on the shaft of a worm wheel 17, with which meshes the worm 18 on the spindle 19 of a press feed motor 20 of the 45 variable speed type. Current is led to the press feed motor 20 through a rheostat 21, having a series of contacts 22 over which travels an arm 23, pivoted at 24 and counter-weighted at 25. Secured to the lever 23 50 is the movable core 26 of a solenoid winding 27 arranged in the circuit 28 of the stone-driving motor 5.

It is obvious that if the load on the grind stone 6 varies, incident to the character of the wood billets 10 which are forced against 55

the stone by the presses, a variation of current in-put to the grind-stone drive motor 5 results, since the stone is driven at constant speed. The consequent variation in the current flow through the solenoid winding 27, influences the position of the solenoid core 26. This displacement of the solenoid shifts the contact arm 23 across the rheostat contacts 22, and a greater or less resistance is thus interposed in the circuit of the press feed motor 20. As a consequence, the drive of the press plungers 8 is accelerated or retarded, and the load on the stone is thus automatically maintained substantially constant. The speed of the stone is thus also 60 maintained substantially constant.

A modified arrangement in which the same result is accomplished is illustrated in Fig. 2, in which the drive of the stone 6 through the belt or chain 7 is taken from the turbine 75 29. The driving belt 7 operates a centrifugal governor 30, to a collar 31 of which is connected one arm of the contact arm 32 which travels over the contacts 22 of the rheostat 21 arranged in the circuit of the feed motor 20 for the press. The latter is here indicated as of different type. Thus the feed motor spindle 19 is provided with two worms 33 and 34, which mesh with worm wheels 35 and 36 on the shafts 37 and 80 38 of the gears which drive the press chains 39 and 40. The latter are arranged at opposite sides of the hopper 41 and engage the opposite sides of the charge of wood blocks 42 and feed the latter against the grind 85 stone 6.

The operation of this installation is analogous to that first described. When the frictional drag of the wood blocks on the grind stone varies, the speed of the turbine 95 29 and the governor 30 is correspondingly affected. The contact arm 32 is thus shifted up or down on the contacts of the rheostat 21 and the current supply to the press feed motor 20 is increased or decreased, thus 100 accelerating or retarding the feed chains 39 and 40. The load on the stone is thus maintained substantially constant, and a drive of the stone at substantially uniform speed attained.

In the construction shown in Fig. 3 the arrangement of the press and its feed motor 20 is substantially identical with that just described. The grind stone 6, however, is 105 driven from a pulley 43 arranged on the 110

crank shaft 44 of a reciprocating engine 45 which may be of any suitable type. The driving fluid or gas admitted to or exhausted from the cylinders of the engine 45 may be led through a pipe 46 to which opens a branch 47 leading to the pressure box 48. Working within the latter is a spring-opposed piston 49, the stem 50 of which is connected to one arm of the contact lever 51 which travels over the contacts 22 of the rheostat 21 arranged in the circuit of the feed motor 20. As the load on the stone 6 varies, the pressure head of the gas or fluid admitted to or from the cylinders of the driving engine 45 varies, and this variation is communicated to the pressure box 48 through the branch 47. The piston 49 is therefore shifted in one direction or the other, and correspondingly shifts the position of the contact lever 51 on the rheostat 21. The speed of the feed motor 20 is thus controlled.

Still another embodiment of my invention is illustrated in Fig. 4, in which the drive of the stone 6 is similar to that shown in Fig. 1. The press plungers 8 are also of the type shown in Fig. 1, but the drive of the gear 17, instead of being taken from an electric motor 20, is taken, in this modification, through a belt or chain 52 passing around a driving pulley or gear 53 on the shaft 54 of a turbine 55. The gas or fluid which drives the turbine 55 enters through the pipe 56 in which is arranged a valve 57, the stem 58 of which is connected to the solenoid core 59, which, as in Fig. 1, is hung from one end of an arm 60 pivoted at 61 and counter-weighted at 62. The winding 63 of the solenoid is arranged in the circuit of the stone-driving motor 5.

The operation is also analogous to those above described. As the load on the stone varies, with consequent variation in the current in-put to the motor 5, the solenoid core 59 rises and falls, and thus varies the position of the valve 57 which controls the flow to the press-feed turbine 55. The feed of the press is thus altered, and the drive of the stone at substantially constant speed is secured.

A further embodiment of my invention is illustrated in Fig. 5, in which the stone 6 is driven, as in Figs. 1 and 4, from a constant speed electric motor. The press is of the type shown in Figs. 2 and 3, comprising feed chains 39 and 40 operated through gears 35 and 36 and worms 33 and 34 on a spindle 19. The latter, however, is driven according to the present modification from a rotary pump 64 operating as a fluid motor. This pump, preferably of the toothed wheel type, drives the pulley 65, on which runs the chain or belt 66 to the pulley 67 on a gear shaft transmitting motion to the bevel gear 68 at one end of

the worm shaft 19. The fluid which drives the rotary pump 64 is delivered thereto from a second pump 69 of the same or different type, the pulley 70 for operating which is driven from the constant speed electric motor 5 through a chain or belt 71, although the pump may be driven from a separate source of power. The fluid upon which the pump 69 operates is contained in a tank 72 and is delivered by the pump 69 to piping 73, through which it passes to the motor pump 64 to actuate the latter which discharges the fluid again to the tank 72.

Arranged in the piping 73 is a control valve 57, the stem 58 of which is connected to the core 59 of the solenoid winding 63 arranged in the circuit of the motor 5. As in the construction shown in Fig. 4, the solenoid is attached at its upper end to the lever 60 pivoted at 61 and counterweighted at 62. As above explained, the current demand of the constant speed motor 5 varies with the load imposed upon the stone 6 by the feed chains 39 and 40. The fluctuation of current varies the position of the solenoid core 59 and thus alters the position of the valve 57 so that more or less fluid is delivered by the pump 69 to the pump 64 which operates the feed chains and thus varies the load upon the grind stone 6 in accordance with the current demand upon the motor 5.

Various other embodiments of my invention will readily occur to those dealing with the problem, without departing from what I claim as my invention.

I claim—

1. In a wood grinder installation, a grind stone, a motor for driving the same, a press for mechanically feeding a charge of wood blocks against the stone, a variable feed rotary motor for advancing the press, and means responsive to the power demand on the stone-driving motor for regulating the effort of the variable speed press-feed motor to maintain the press load on the stone substantially constant.

2. In a wood grinder installation, a grind stone, a motor for driving the same, a press for mechanically feeding a charge of wood blocks against the stone, a variable feed rotary motor for advancing the press, a member movable with and subject to fluctuations in the power supply to the driving motor incidental to the drive of the stone at constant speed, and means operatively associated with said movable member for regulating the power in-put to the variable speed press-feed motor to maintain the press load on the stone substantially constant.

3. In a wood grinder installation, a grind stone, a motor for driving the same, a press for mechanically feeding a charge of wood blocks against the stone, a feed gear for

advancing the press, a variable speed electro-motor for driving the feed gear, and means for controlling the speed of the variable speed electro-motor to maintain substantially constant the load on the grind stone. 10

4. In a wood grinder installation, a grind stone, a motor for driving the same, a press for continuously feeding a charge of wood

blocks against the stone, a feed gear for advancing the press, a variable speed electro motor for driving the feed gear, and means for controlling the speed of the variable speed electro motor to maintain substantially constant the load on the grind stone. 15

In testimony whereof I have signed my name to this specification.

PAUL PRIEM.
